UNITED STATES PATENT OFFICE

96,569

DESIGN FOR A FINGER RING OR SIMILAR ARTICLE

Stanley Zimba, Pennsbury, Pa.

Application May 25, 1935, Serial No. 57,024

Term of patent 3½ years

To all whom it may concern:

Be it known that I, Stanley Zimba, a citizen of the United States, residing at Pennsbury, in the county of Montgomery and State of Pennsylvania, have invented a new, original, and ornamental Design for Finger Ring or Similar Article, of which the following is a specification, reference being had to the accompanying drawing, forming part thereof.

I claim:

The ornamental design for a finger ring or similar article, as shown.

STANLEY ZIMBA.
